UNITED STATES PATENT OFFICE

LOUIS NYCZ, OF BINGHAMTON, NEW YORK

VENDING MACHINE FOR CIGARETTES AND MATCHES

Application filed August 1, 1928. Serial No. 296,687.

My invention relates to penny in the slot vending machines for cigarettes and matches, and it has for its object to provide a simple accurate device for the purpose of delivering a cigarette and match on the insertion of a penny in the machine itself, and which will automatically deliver the cigarette and match.

Another purpose of my device is to provide 10 a penny vending machine for cigarettes and matches which cannot be readily put out of order and from which the coin cannot be removed, and in which spurious coins or weights cannot be well inserted and a cigarette or match automatically delivered thereby.

With these and other objects in view my invention consists in certain novel features of construction and arrangement of parts as will 20 be hereinafter more fully described and pointed out in the claims. Reference being had to the accompanying drawings in which:

Fig. 1 is a side view in cross section of my device.

Fig. 2 is a front view partly in cross section of my device.

Fig. 3 is a side view partly in cross section showing the cigarette and match delivery.

Fig. 4 is a plan view partly in section on 30 line 4, 4 of Fig. 3.

Fig. 5 is a perspective view of the rotary gate.

Fig. 6 is a perspective of the coin controlled disk.

The same reference characters denote like 35 parts in each of the several figures of the drawings.

As a part of my device I have the casing or structure A. Mounted therein, I have the 40 penny slot B opening from the top of the casing or any convenient point. Mounted within the casing I have a channel C in which may be placed a plurality of matches Z, the end views of which are shown in Figs. 1 and 3; the channel C has an opening or receiver marked C'. Mounted also in the casing I have a channel D, in which may be placed a quantity of cigarettes for vending purposes. The channel D has sloping walls and terminates in the mouth J.

As a further part of my device, pivotally mounted in the casing A, I have a lever 2, mounted upon the pivot 3, the lever 2 has for its upper end the projecting point 4 which projects thru a slot in the side of the channel B. Pivotally mounted on the lower end of lever 2 I have a sliding gate 5, having therein an elongated slot 6, the gate 5 being normally projected outwardly by means of the spring 55 3a.

As a further part of my device I have extended thru the structure A, the shaft 7, also mounted within the same I have a container E having the sloping sides 8 and having an open spout 9 and mounted on shaft 7 I have the triangular gate F, having the opening and closing wings 10, 10. Pivotally mounted on shaft 7, I have the two disks G, G, spaced apart opposite, and forming two parallel walls and mounted between the walls on disk G, I have the treads 11, and also in alinement with the tread 11, I have the bucket 12. The channel B extends on down in alinement with the disks until it is projected in the curved chamber H, and opens into the coin receiving box I. Mounted in alinement with the disk G, I have the notched disk J', having the notches therein 13, 13, and pivotally mounted on pivot 14, I have the latch 15, which has pivotal contact with the notch 13, and at the other end of latch 15, I have the arm 16, the end of which vibrates opposite the tread 11. In the channel D I place the cigarettes J, J. On the end of shaft 6, I have mounted the turn button or knob K to turn 60 65 70 75 80 85 90 95 100 the gate.

In the operation of my device having mounted in the channel C, the quantity of matches Z and also in the receiver D, the cigarettes J, J, J, to be delivered, I place in the channel B a coin X. In placing the coin X in the large channel V it contacts with the point 4 on the lever 2, and pushes back the lever 2 which pushes the slide 5, which moves the slot 6 to a position opposite the mouth of the match chute holder C and thus releases a match Z. The coin then passing on down the chute B goes down the channel B until it strikes the tread 11, and the arm 16 of latch 15 which turns on pivot 14 and

moves the arm 15 out of contact with the notch 13 in the disk J, revolving on the shaft 6, the turning of which turns the cigarettes J, which drop down into the tube Y. The coin proceeds on its way past the latch 15 and down the tube H into the coin box I. The gate having revolved, the wing 10 comes in front of the mouth of the cigarette receiver D, until another coin is dropped and the latch is released from the notch 11 and the gate turns and releasing another cigarette. In the tube Y there is the opening for the insertion of a hand to remove the cigarette, and thus automatically, by the insertion of the coin within the machine there is automatically dropped a match or matches from the upper slot 5, and into the receiver and also a cigarette is dropped, passing down into the receiver Y, all at the same time and the same action.

As a further part of my device I have mounted on the end of the shaft 7K, a knob to aid in the end manipulation of the machine and turns by hand the gate, and I thus forward to the receiver a cigarette by hand motion, while the penny falling into the tube opens the latch and permits the gate to act.

Having thus described my invention what I claim as new and for which I desire Letters Patent is as follows:

1. In a coin-controlled vending machine, a casing, a coin chute therein, a horizontal shaft rotatably mounted in the casing, a pair of discs spaced apart and mounted on the shaft near one end thereof, treads disposed between the discs, a notched disc mounted on said shaft, a latch pivotally mounted intermediate its ends within the casing, a hook on one end of the latch for engagement with the notches in the notched disc, the other end of the latch being disposed in the coin chute and a knob on the outer end of the shaft for manually turning the latter.

2. In a coin-controlled vending machine, a casing, a coin chute vertically disposed within the casing, a horizontal shaft rotatably mounted within the casing adjacent the coin chute, a pair of discs spaced apart and mounted on said shaft, treads disposed between the discs with the discs so located with respect to the coin chute as to permit a deposited coin to rest on one of said treads, a notched disc also mounted on said shaft, a pivoted latch within the casing, a hook on one end of the latch for engagement with the notches in the notched disc, the other end of the latch projecting between the treads of the discs so as to be disposed in the path of a coin to release the latch and permit turning of the shaft, and a knob for operating the shaft when released.

3. In a coin-controlled vending machine, a casing, a coin chute within the casing, and provided near its lower end with an offset section provided with a cut-out portion, a

pair of discs projecting into the cut-out portion of the coin chute, a shaft on which said discs are mounted, treads disposed between the discs, a notched disc also mounted on said shaft, a latch pivotally mounted within the casing, a hook on one end of the latch for engagement with a notch in the notched disc to normally lock the shaft against rotation, an arm at the other end of the latch normally projecting between the treads of the pair of discs and into the coin chute in the path of a coin deposited in the chute for moving the arm and withdrawing the hook out of one of the notches in the notched disc, and a knob for the manual turning of the shaft.

In testimony whereof I have affixed my signature.

LOUIS NYCZ.
